UNITED STATES PATENT OFFICE

137,833

DESIGN FOR AN AUTOMOBILE BODY

John Robinson, Los Angeles, Calif.

Application May 2, 1941, Serial No. 100,742

Term of patent 7 years

(Cl. D14—3)

To all whom it may concern:

Be it known that I, John Robinson, a citizen of the United States of America, residing at Los Angeles, in the county of Los Angeles and State of California, have invented a new, original, and ornamental Design for Automobile Bodies, of which the following is a specification, reference being had to the accompanying drawing, forming part thereof.

Fig. 1 is a side elevational view of an automobile body, showing my new design.

Fig. 2 is a top plan view; and

Fig. 3 is a front elevational view thereof.

I claim:

The ornamental design for an automobile body, as shown.

JOHN ROBINSON.
